UNITED STATES PATENT OFFICE.

HIRAM PHELPS ARMS, OF WEST HARTFORD, CONNECTICUT, ASSIGNOR OF
TWO-THIRDS TO EDGAR C. LINN, OF WEST HARTFORD, CONNECTICUT.

PROCESS OF PRODUCING PLATES FOR PRINTING.

SPECIFICATION forming part of Letters Patent No. 740,352, dated September 29, 1903.

Application filed August 21, 1901. Serial No. 72,821. (No specimens.)

To all whom it may concern:

Be it known that I, HIRAM PHELPS ARMS, a citizen of the United States, and a resident of West Hartford, Hartford county, State of Connecticut, have invented certain new and useful Improvements in Processes of Producing Plates for Printing; and my preferred manner of carrying out the invention is set forth in the following full, clear, and exact description, terminating with claims particularly specifying the novelty.

This invention relates to a process for forming high-relief plates for typographical printing, and it is particularly adapted for forming plates for printing in colors with crayon effects on common type-presses.

By prior lithographic processes the conceptions of the artist are reproduced upon stone by the aid of photography and also are delineated directly upon stone with lithographic ink or crayon. Both of these methods necessitate the exercise of particular skill in the manipulation of various instruments and chemicals employed and require the use of a slow lithographic press for printing, as the conceptions are not etched and reproduced on the stone in high relief.

By previous engraving processes the conceptions are reproduced upon metal plates by the aid of photography and also are delineated upon surfaces prepared on metal plates by the application of granular material made to adhere to the plate by the action of heat. These methods necessitate the employment of chemicals in preparing the plates, which raise the cost, increase the labor, and, while they produce etched plates in high relief which may be used in typographical presses, the delineations cannot be altered and changed at will and numbers of accurately-registering offsets cannot be easily obtained.

The object of this invention is to provide a simple, cheap, and rapid process of forming metal printing-plates that has such procedure that the artist may give full expression to his conceptions directly upon the metal surfaces of the plates, which will thus receive the impress of his individuality and that will permit the artist to freely erase, correct, and alter the delineations and take off as many accurately-registering offsets as desired directly

from the key-plate for forming the color-plates.

Figure 1 of the drawings represents a conception being delineated with an etching-resist directly upon the mechanically-grained surface of a dense metal plate. Fig. 2 represents a small section of a plate before it has been grained. Fig. 3 represents a section of a plate with the surface grained. Fig. 4 represents the application of resist to portions of the grained surface of a plate. Fig. 5 represents a section of the plate with the grained portion of the surface that is not protected by the primary resist removed by the etching-acid. Fig. 6 represents a section of the plate with the surface still further etched. Fig. 7 represents the section of the plate with the surface that is unprotected etched deeper. The grained portions of the sections of the plates shown in these views are greatly magnified. Figs. 8, 9, and 10 show sections of the plate magnified still more, illustrating the manner of protecting the points which have been protected by the primary resist by the strengthening-resist until the plate has been etched to the required depth.

In carrying out this process the conception of the artist is delineated by strokes, lines, or stippling with the ordinary lithographic crayon or ink, containing lampblack and grease or similar acid-resisting materials, directly upon the plate 1, preferably zinc, that is perfectly level and has a uniform granular surface 2 mechanically produced by sand applied by an ordinary graining-machine.

The projecting grains on the surface of the plate retain the particles 3 of acid-resisting materials that are abraded from the delineating-crayon 4, and of course when the strokes or lines are light but little crayon will be abraded and will protect the metal but little, so that light tones will result, and when the strokes or lines are heavy more crayon will be abraded and will protect the metal considerably, so that dark tones will result.

If it is desired to make a correction or alteration to the crayon delineation on the plate, the portion desired removed can be ground out by the aid of a flat piece of glass and sand and then redrawn and the process continued. This mechanically-grained metal plate with

the conception delineated directly upon it in crayon is without further preparation immersed in a rather weak solution of nitric acid for a short time, perhaps half a minute. 5 The lampblack and grease of the crayon form a sufficient resist for this short immersion in the weak acid-bath that accomplishes the preliminary etching, so that the conception is reproduced in a very light relief upon the 10 plate. In fact, the relief at this stage is so light as to be hardly noticeable to the eye. The plate is removed from this preliminary bath and dried under a gentle heat, and then a resisting-powder, preferably dragon's-blood, 15 is spread upon it. Particles 5 of this powder adhere to the particles of crayon and strengthen the resisting capacity of the crayon, and after the superfluous powder is shaken off the plate is immersed in the etching-bath for approximately one minute. After 20 removing and thoroughly drying acid-resisting powder is sprinkled upon the plate and brushed off in one direction with a fine brush, preferably a camel's-hair brush. After 25 heating the plate hot and allowing it to cool it is again sprinkled with resisting-powder. This is brushed off in a different direction. The heating and cooling of the plate and the sprinkling of powder are performed 30 four times, each time the powder being brushed off in a different direction. As a result of this the resisting-powder is banked on each side of the minute particles of metal that have been protected from the action of the acid beneath 35 the grains of crayon, and so protects the raised points that the acid will not eat under them when the plate is again immersed in the etching-bath. The plate is then immersed in the etching-acid approximately 40 from four to six minutes, according to the judgment of the etcher. After drying the plate is again heated, powdered, and brushed four times, as before, and then immersed in the acid approximately from five to six minutes, as desired. The plate is then dried and 45 preferably rolled with proof printing-ink, heated, powdered, and brushed four times, as before, and immersed in the acid-bath approximately from seven to eight minutes, according 50 to judgment. The plate is then dried, trimmed, and mounted on a block type high and is ready to use in the ordinary printing-press.

By the practice of this process soft crayon effects can be obtained with a metal plate such as formerly could only be obtained with stone.

In making offsets for color-plates the key-plate is inked and as many proofs taken from 60 it as there are to be colors used. Before the ink on these proof impressions becomes dry it is dusted with powdered red chalk. This powder adheres to all the details of the printed impression, and the superfluous chalk is shaken off. As many mechanically-grained plates as there are colors to be used 65 are cut to the size of the original and dam-

pened with turpentine free of all greasy matter. The chalk-covered proofs are then placed upon the grained metal surfaces of 70 the color-plates and put in a proof-press and an impression in chalk is taken. The turpentine that has been used to dampen the plates evaporates, leaving a clear impression of the original drawing, upon which the artist 75 proceeds to draw for the color as necessary. The color-plates are then treated in exactly the same manner as the original key-plate. As the surfaces of the plates are not chemically prepared and there are no films to handle, the offset impressions are exact copies of the original, so that the colors will register accurately.

In the practice of this process the minute quantity of lampblack or other fatty matter 85 contained in the crayon forms the first resist for the etching mordant, thus enabling the etcher to retain the lightest tones of the conception until the relief is sufficient to receive the powder which forms the secondary resist 90 and strengthens the crayon primary resist. This fact allows the reproduction of conception in crayon effects without originally drawing the conception upon paper and by photographic methods transferring it to the plate. 95 These plates, which will accurately register, may be used on any ordinary printing-press.

I claim as my invention—

1. The herein-described process of forming high-relief plates for typographical printing, 100 which consists in delineating the conception to be reproduced with an etching-resist directly upon a mechanically-grained surface of a dense metal plate, subjecting the plate with the conception thus delineated without further treatment to a bath containing an etching solution and lightly etching the surface of the plate, then removing the plate from the bath and repeatedly strengthening the primary etching-resist by the addition of resisting-powder and immersing the plate with the primary resist thus strengthened in the etching-bath until the plate has been so etched that the conception stands in high relief, substantially as described. 115

2. The herein-described process of forming high-relief plates for typographical printing, which consists in delineating the conception to be reproduced with an etching-resist directly upon a mechanically-grained surface 120 of a dense metal plate, subjecting the plate with the conception thus delineated without further treatment to a bath containing an etching solution and lightly etching the surface of the plate, then removing the plate 125 from the bath and repeatedly strengthening the primary etching-resist by the addition of acid-resisting powder and immersing the plate with the primary resist thus strengthened in the etching-bath until the plate has been so 130 etched that the conception stands in high relief, inking the key-plate thus produced, taking offsets from the key-plate in proof-ink, dusting the proofs before dry with red pow-

der, impressing the red-powdered proofs directly upon the metal surfaces of mechanically-grained plates, delineating upon the plates the parts desired to be printed by the individual plate, and etching these plates the same as the key-plate, substantially as described.

In testimony whereof I have hereunto subscribed my signature this the 21st day of August, A. D. 1901.
